AMPHIBIAN AIRPLANE

Filed Feb. 7, 1930

UNITED STATES PATENT OFFICE

TOM TOWLE, OF DETROIT, MICHIGAN, ASSIGNOR TO TOWLE AIRCRAFT COMPANY, OF DETROIT, MICHIGAN, A CORPORATION OF MICHIGAN

AMPHIBIAN AIRPLANE

Application filed February 7, 1930. Serial No. 426,454.

This invention relates to amphibian airplanes, that is to say that it is that type of airplane adapted to land on both sea and land.

The object of this invention is to arrange 5 so that the landing wheels can be conveniently withdrawn into an inoperative position in floats when landing on the sea and can be returned to the operative when required for land use with the least possible effort on the 10 part of the pilot.

Figure 1 is a layout showing the essential elements of this invention.

Figure 2 shows in partial section the front elevation of the airplane to which this invention is applied.

Figure 3 shows a side elevation showing in full lines the landing wheels in an operative position, and in dotted lines the wheels in the inoperative position.

Figure 4 shows the control valve in the position for raising the wheels.

Figure 5 shows the valve in the position for locking the wheels either up or down.

Figure 6 shows the valve in the position to 25 lower the wheels.

Figure 7 shows the valve in the position for gravity lowering.

In the figures, A is an airplane engine complete with propeller V, B is an oil pump 30 adapted to be driven by the engine, C is an oil tank feeding the pump through a pipe D, E is the delivery pipe leading from the pump B to the control valve F, (see Figures 4, 5 and 6) this control valve is provided with 35 4 connections, E, J, G, H, and a passage W through the center.

Pipe E enters the control valve F on top, the return pipe G leaving from the bottom. When the valve F is in the position as shown 40 in Figure 5, the oil freely circulates through C, D, B, W, G, and back to C. The other 2 pipes H and J communicate with the opposite side of the piston K which is adapted to slide in a cylinder L. A pressure gauge located 45 on the dash is connected to each of these pipes H and J. The piston rod K' is pivotally connected with a triangular truss M, which carries the landing wheel O. This truss is carried inside a housing U which is 50 supported by the wing R and also by the

truss T which extends out from the hull N and through which the wheel O passes, and supports the wing float N' having an opening N''. The truss M is pivotally connected to the wing float N' at the point Q, the housings U—U extend from wing R to the wing floats N'—N' and support the same. A hydraulic shock absorber S of a well known type is mounted at the upper end of the cylinder L. The upper end of this shock absorber S is pivotally connected at the point P with the wing R. In order to prevent excessive pressure in the pipe system due to the pump action, a return pipe X is provided with a suitable pressure relief valve (Fig. 1). 65

Operation

As already stated when the valve F is in the position shown in Figure 5, the oil circulates freely from B to E through F and 70 back to the tank C by way of the pipe G passing through the passage W in the center of the valve F; with the valve in this position, the piston K is not moved and is therefore locked. When the valve is in the position shown in Figure 4, oil passes from E to J (and also from H to G and so back to C). The piston K is thus forced up inside the cylinder L thus raising the wheel O and permitting the plane to land on the water. 80

When the valve is in the position shown in Figure 6, oil flows from E to H and also from J to G and so back to C. The piston K is thus forced down in L and the wheels are lowered into the position shown in Figure 85 3 and the plane is converted back into a land machine once more.

When the valve is in the position shown in Figure 7, the oil flows from J to H and thus allows the piston to be lowered by gravity. 90

It will be noted that the wheels are in duplicate and hence both wheels are moved simultaneously, duplicate pipes extending from the valve F to each wheel control. For the sake of simplicity only one set of piping 95 is shown.

What I claim is:

1. An amphibian airplane having wings, wing floats having a fixed position relative to the wings, a pair of wheels each mounted 100

on a truss pivotally supported both by said wing floats and by said wings, a suitable opening in each of said wing floats, means for withdrawing the wheels through said 5 openings.

2. An amphibian airplane having wings, wing floats in combination therewith having a fixed position relative to the wings, a pair of wheels each mounted on a truss pivotally 10 supported both by said wing floats and by said wings, a suitable opening in each of said wing floats, means for withdrawing the wheels through said openings, shock absorber means located at the points on the wings 15 to which the trusses are pivotally connected.

In testimony whereof I affix my signature.
TOM TOWLE.
